CLAIM

The ornamental design for a link and pin assembly for watch strap, as shown and described.

DESCRIPTION

FIG. 1 is a top perspective view of a link and pin assembly for watch strap showing one link and one pin removed for ease of illustration.

FIG. 2 is a top plan view of thereof.

FIG. 3 is a sectional view taken along line 3-3 indicated in FIG. 2.

FIG. 4 is a top perspective view of the link and pin assembly for watch strap showing two links and no pin for ease of illustration.

FIG. 5 is a top perspective view of the link and pin assembly for watch strap showing two links and the pin removed for ease of illustration.

FIG. 6 is a top perspective view of the link and pin assembly for watch strap showing two links and one pin.

FIG. 7 is a top plan view thereof.

FIG. 8 is left side elevation view thereof; and,
FIG. 9 is a sectional view taken along line 9-9 as indicated in FIG. 8.
